UNITED STATES PATENT OFFICE.

REUBEN HITCHCOCK, OF CLEVELAND, OHIO, ASSIGNOR TO THE CLEVELAND FOLDING MACHINE COMPANY, OF CLEVELAND, OHIO, A CORPORATION OF OHIO.

SHEET-FEEDING MACHINE.

Application filed May 23, 1925. Serial No. 32,329.

To all whom it may concern:

Be it known that I, REUBEN HITCHCOCK, a citizen of the United States of America, residing at Cleveland, in the county of 5 Cuyahoga and State of Ohio, have invented certain new and useful Improvements in Sheet-Feeding Machines, of which the following is a specification.

My invention relates to improvements in 10 sheet feeding machines, and more particularly, to the type of paper feeding machines known as the pile feeder, wherein the sheets are stacked upon an intermittently elevated supporting table and successively 15 presented to the feeding device, such as a rotary suction head.

The object of my invention is better to adapt a sheet feeding machine of this type for use with sheets of different sizes; making 20 the forward portion of the supporting table normally accessible to the operative in loading and positioning the smaller sheets, while providing means for accommodating sheets of maximum size.

25 In order to accomplish the objects of my invention, the pile feeder, preferably operated by means of worm gears and elevating chains, synchronously rotated by any suitable means, is constructed of rearwardly 30 open type to permit the ready access of the operative, so that he may reach the forward edge of the supporting table while placing and adjusting sheets of moderate size. The supporting table preferably is constructed 35 with substantial lateral frames carried directly by the elevating chains; said frames being adapted to accommodate one or more extension members for supporting the larger sizes of sheets. Moreover, owing to the excessive 40 weights of paper which a pile feeder preferably must accommodate, I provide removable cross-bracing means for rearwardly staying the open frame of the machine.

The details of a construction embodying 45 my improvements may best be explained by making reference to accompanying drawings wherein:

Figure 1 is a plan view of a sheet feeding mechanism incorporating my improvements and equipped to handle the largest 50 sizes of sheets.

Fig. 2 is a vertical sectional view on line 2-2, Fig. 1.

Fig. 3 is a rear view of the sheet feeding 55 mechanism.

Fig. 4 is a fragmentary plan view partially broken away, illustrating details of the adjustable supporting table.

Fig. 5 is a fragmentary sectional view on line 5-5, Fig. 4.

Fig. 6 is a similar view on line 6-6, Fig. 4, and

Fig. 7 is a fragmentary view illustrating the locking means for the bracing member.

Throughout the several figures of the drawings, I have employed the same character of reference to indicate similar parts.

Figs. 1 and 2 are readily recognizable as substantial illustrations of the essential features of an approved type of pile feeder wherein the adjustable supporting table is positioned to be elevated intermittently toward the feeding level, from which a rotary suction head successively advances the sheets 75 upon a roller feed table shown at the left partially broken away. The mechanism for intermittently operating the supporting table may be of approved type but since it forms no part of my present improvement, 80 the details thereof do not require illustration or description herein. It will be sufficient to say that the worm gears *a*, *a* are driven by a common shaft *b*, terminally 85 mounting reversely cut worms *b'*, which engage said gears. These gears are mounted upon and rotate the longitudinal shafts *c* carrying the sprocket wheels *c'* *c'*, over which the elevated chains *d*, *d* extend for concurrent actuation. These chains are attached adjacent to the corners of an angle bar frame *e*, *e*, adapted to receive the sectional boards *f*, *f'* and *f''*, which separately or together constitute the supporting surface of the feed table.

95 For sheets of ordinary size the supporting board *f* alone is adjusted within the frame *e* and access is readily obtained thereto even to its forward edge, merely by lifting the bracing bar *g*, which is pivoted upon one 100 of the rear pillars *g'* and is adapted to hook over a stud *g''* upon the other pillar *g''*; said pillars rearwardly supporting the bearings of the shafts *c*, *c* which carry the weight of the paper.

105 This brace is of considerable importance under normal working conditions, since a fully loaded supporting table may carry sheets aggregating a ton in weight, yet, as previously indicated, it is extremely desir- 110

able to permit the access of the operative to the forward edge of the supporting table, as when small sheets must be disposed and properly positioned thereon. In order to prevent the bracing member from accidentally falling from its elevated position, it is provided with a spring actuated detent h , while a stop h' prevents said member from swinging too far beyond an outwardly inclined position when said member is raised as shown in Fig. 3.

The adjustable section f' of the supporting table is inserted between the angle bars e when sheets of moderate size are to be handled by the sheet feeding mechanism, the same being provided with clips f'' which are adapted to take beneath the forward section f and preserve the alignment of the members. Similarly, a double clip f'' is provided rearwardly of the member f' and upon each side thereof, as shown in Figs. 4 and 6, whereby the angle frame is outwardly engaged and the extensions of the angle bars f'' , provided beneath the section f'' are engaged and braced for supporting the outer member of the supporting table when sheets of the largest size are handled.

The feeding level of the sheet feeding mechanism is maintained substantially at the height of apron i and rollers i' of the sheet delivery table (Fig. 2), which rollers are driven by the under-running belt i'' extending over the drum i'' .

Any suitable feeding member may be employed, but preferably a pneumatic suction head j , continuously rotated in clockwise direction by shaft j' , is employed for successively advancing the sheets toward the left. Details of this sheet feeding member do not require explanation but they may correspond to those set forth by the disclosure in my co-pending application, Serial No. 755,797, December 13, 1924.

As the sheets are fed from the forward edge of the pile, supported by one or more of the feed table sections f , f' and f'' , according to the length thereof, the table is elevated by rotating the shaft b and its associated gears and shafts c , c in any suitable manner, so that the level is maintained, approximating the lower face of the rotary suction head j , whereby the paper is fed sheet by sheet toward the left upon the delivery table and to any associated printing or folding mechanism. As the pile becomes nearly exhausted, the operation of the sheet feeding mechanism is temporarily checked, the supporting table is lowered to accommodate another pile of sheets and the bracing bar g is elevated as shown by dotted lines in Fig. 3 to permit the free access of the operative to the forward portion of the supporting table, if necessary, in order properly to dispose another pile of sheets

in position to be fed by the rotary suction head.

The bracing bar maintains the rearward alignment of the shafts and the positioning of their supporting pillars when in its lowered relation, while freeing the otherwise open frame for the insertion or removal of the sections of the supporting table and the renewal of the paper pile thereon. These sections are interlocked and maintained in alignment by the chain-supported angle frame, so that excessive weights are handled with convenience and ease, even when the largest size sheets are fed by the machine.

Automatic means such as shown in Tufts, Ser. No. 22659, for example, may be used to maintain the feeding level of the paper.

Having now described my invention and its principal advantages and mode of operation, I claim as new and desire to secure by Letters Patent, the following:

1. In a sheet feeding machine of the class described, the combination with a sheet-supporting table, of elevating mechanism, laterally applied thereto, including lateral shafts supported in a rearwardly open frame, and cross-bracing means removably positioned transversely of the frame adapted to preserve the alignment of the shafts, substantially as set forth.

2. In a sheet feeding machine of the class described, the combination with a rectangular supporting frame, of means for elevating said frame to the feeding level of the machine and a plurality of insertable sections adapted to be placed upon said supporting frame for accommodating said sheets of different sizes, substantially as set forth.

3. In a sheet feeding machine of the class described, the combination with a sheet-supporting table, comprising a frame and a plurality of insertable supporting sections, of laterally positioned elevating means applied to said frame, including lateral shafts and driving mechanism therefor; said shafts being mounted in a rearwardly open frame, whereby access to the forward portion of the supporting table may readily be obtained by the operative, substantially as set forth.

4. In a sheet feeding machine of the class described, the combination with a rectangular supporting frame, of elevating means therefor, and a plurality of supporting members adapted separately to be inserted in said frame, and interlocking means provided upon said members for insuring their alignment, substantially as set forth.

In testimony whereof I do now affix my signature.

REUBEN HITCHCOCK. [L.S.]
